UNITED STATES PATENT OFFICE.

CHARLES H. LUDWIG, OF NEW YORK, N. Y.

IMPROVEMENT IN CHAMPAGNE-FREEZERS.

Specification forming part of Letters Patent No. 166,996, dated August 24, 1875; application filed July 31, 1875.

To all whom it may concern:

Be it known that I, CHARLES H. LUDWIG, of the city, county, and State of New York, have invented a new and Improved Champagne-Freezer, of which the following is a specification:

The accompanying drawing represents a vertical central section of my improved champagne-freezer.

The object of my invention is to furnish for hotels, restaurants, &c., an improved champagne cooler and freezer, by which champagne and other beverages may be cooled rapidly in a very convenient manner.

The invention will first be described in connection with drawing, and then pointed out in the claims.

In the drawing, A represents an ice-cooler or other receptacle, to which the standard or frame B is applied in fixed or detachable manner, as desired. A central vertical rod, C, is revolved in cross-bearings at the top part of frame B by suitable gearing operated by a crank-handle, rod C being provided at the lower end with a fixed cross-piece, D, to which jaws E, that are fitted to the necks of cham-

pagne or other bottles, are hinged. A clamp-bolt and screw-nut, F, connects the hinged jaws, and admits their rigid attachment to the bottle for being revolved by rod C, and thereby quickly acted upon by the ice in the ice-receptacle A.

Any beverage may thus be cooled in very short time, and the "champagne grappée" be made in quick and convenient manner by means of a handy and time-saving implement.

Having thus described my invention, I claim as new and desire to secure by Letters Patent—

1. The combination, with revolving shaft C, suspended in frame over cooler, of the cross-bar D, provided with pivoted arm E at each end, the said arms having corresponding end jaws, as and for the purpose specified.

2. The combination, with arms E E, of screw F, pivoted to one arm, and passing through the other, and provided with clamp-nut, as and for the purpose described.

CHAS. H. LUDWIG.
